(57) **CLAIM**

The ornamental design for a device for barcoding individual wells and vessels, as shown and described.

DESCRIPTION

FIG. 1 illustrates a perspective view of a device for barcoding individual wells and vessels employing an ornamental design in accordance with the present invention; FIG. 2 illustrates a top view of the barcoding device of FIG. 1;

FIG. 3 illustrates a front elevational view of the barcoding device of FIG. 1;

FIG. 4 illustrates a rear elevational view of the barcoding of Figure FIG. 1;

FIG. 5 illustrates a bottom view of the barcoding device of FIG. 1;

FIG. 6 illustrates a left side elevational view of the barcoding device of FIG. 1;

FIG. 7 illustrates a right side elevational view of the barcoding device of FIG. 1;

FIG. 8 illustrates a perspective view of the barcoding device; and,

FIG. 9 illustrates a perspective view of the barcoding device with a vessel nestled within the barcoding device of FIGS. 1 and 8.
